[57]

ABSTRACT

An automatic pin injector for positioning pins within an axial bore of a grill bar including a spring biased plunger axially reciprocal from an initial position to a driving position, a forward pin chamber section which receives the end of a grill bar therein, the pin chamber section including an intake slot and pin pick up which is initiated by the insertion of the grill bar within the intake slot and a micro switch which trips upon seating the grill bar within the intake slot, an air cylinder responsive to operation of the micro switch to pull the plunger rearwardly against the bias of one of its springs, a plunger release which functions upon the rearward movement of the plunger to release the plunger and a plunger spring to propel the plunger forwardly to drive a pin into the axial bore upon function of the plunger release.

FIG. 7

AUTOMATIC PIN INJECTOR

BACKGROUND OF THE INVENTION

This invention relates to the general field of decorative window grills, and more particularly, is directed to an automatic pin setting machine designed to facilitate the installation of pins into the axial bores of grill bars for removably securing a decorative window grill to a window frame.

In view of the increasing costs involved in the prior art practice of manufacturing windows having four, six or eight individual lights of glass which are retained within a wooden frame by employing a plurality of horizontal and vertical frame bars, it has become increasingly more popular to manufacture window sash having but a single pane of glass which is affixed within a peripheral wooden or metallic frame. By employing such a single glass pane and an undivided frame construction, all of the millwork formerly associated with the multi-light type of window fabrication can thus be eliminated, thereby resulting in substantial production cost savings. In this manner, window manufacturers can now produce and offer for sale at substantially lower prices, a sash having but a single light of glass.

In order to maintain the aesthetically pleasing appearance of the multi-light type of sash, and at the same time gain the advantages and production economies made possible by the single light type of construction, the use of removable, decorative grill bar assemblies has gained increasingly wide spread acceptance. Decorative grills constructed of both wood and plastic bars have been employed by prior workers in the field and present trends indicate greatly increased use of such grills in the future. The method of removably fastening the decorative bars to the window sash has always proved to be a problem and considerable time and effort has been spent by prior workers in the field to design acceptable attaching means. One such attaching means has been disclosed in the patent to Martin, U.S. Pat. No. 3,358,412 wherein a collar pin installation is shown in connection with grill bars having axial bars.

The said collar pins have been used to insert directly into the wooden sash immediately in front of the glass and to leave an exposed head which engages the axial bore to the window frame. The present invention relates to the same general problem and incorporates an automatic pin injector which is employed to position pins partially within the axial bore of the grill bars prior to applying the grill bars to a window frame. Means would then have to be provided in the frame to removably receive the exposed end of the pin.

Machines for applying pins to the wooden members such as window frames are known, and these machines are adapted to handle pins which are oriented in the same direction, which are aligned adjacent to each other and which are held as a single unit by an adhesive tape system. One such machine is disclosed in an application by Paul S. Newswanger, entitled "Decorative Grill Pin Setting Machine", Ser. No. 863,177, filed Oct. 2, 1969, now U.S. Pat. No. 3,623,648, issued Nov. 30, 1971, and assigned to the assignee of this application. In the said co-pending application, the machine handles pins which are approximately one-fifteenth of an inch in diameter, one-half inch long and which are pointed at one end. The prior art machine automatically inserts these pins into window sashes with the pointed ends inserted and with the blunt ends exposed

to accommodate plastic window dividers having axially aligned bores which can be snapped in place over the pins. The present machine is similar in concept and functions to position the pins directly in the axial bores of the grill bars prior to application over a window frame.

The present invention relates to an automatic pin injection machine which is designed to facilitate the positioning and installation of grill retaining pins in an automatic manner and serves to provide an extremely inexpensive, rapid and infallible device for positioning and driving grill retaining pins into the exposed ends of axially aligned bores of individual grill bars.

The automatic pin injector of the present invention 15 incorporates a forward pinning section which is provided with a shaped intake opening to receive one end of a grill bar for pin insertion purposes. As the grill bar feeds into the pinning section, it trips a pin pickup device to automatically feed a pin into the pin chamber 20 in axial alignment with the axial bore of the grill bar. When the grill bar fully seats within the pinning section, the end of the grill bar trips a micro switch to function an air cylinder which powers the apparatus for pin injection purposes. The air cylinder operates to pull a spring biased plunger rearwardly relative to the inserted end of the grill bar. The plunger is releasably connected to the air cylinder draw arms by means of a pivotal trigger which is pulled in rearwardly upon operation of the air cylinder. The pivotal trigger is rearwardly pulled into a stationary release which functions to pivot the trigger to release the plunger. A plunger spring urges the plunger forwardly until it strikes the previously aligned pin and drives it a predetermined distance into the axial bore of the grill bar. After each 30 driving operation, the air cylinder recycles to reposition the trigger for releasable connection to the plunger. By utilizing the present device, the grill retaining pins may now be rapidly, positively and automatically positioned within the ends of grill bars at the factory to thereby eliminate all of field handling and time consuming operations on the job site.

It is therefore an object of the present invention to provide an improved automatic pin injector of the type set forth.

45 It is another object of the present invention to provide a novel automatic pin injector that is designed to automatically and rapidly insert a grill pin into the axial bore of a decorative grill bar.

50 It is another object of the present invention to provide a novel automatic pin injector that considerably accelerates grill pin insertion procedures by providing positive and accurate, factory installed pin driving procedures.

55 It is another object of the present invention to provide a novel automatic pin injector that is rugged in construction, simple in design and trouble free when in use.

Other objects and a fuller understanding of the invention will be had by referring to the following description and claims of a preferred embodiment thereof, taken in conjunction with the accompanying drawings wherein like reference characters refer to similar parts throughout the several views and in which:

BRIEF DESCRIPTION OF THE DRAWINGS

FIG. 1 is perspective view of an automatic pin injector in accordance with the present invention.

FIG. 2 is a top plan view thereof.

FIG. 3 is a partial, enlarged, top plan view of the pinning section and pin chamber, partially broken away to expose details of interior construction.

FIG. 4 is a side elevational view of the pinning section and pin chamber taken along Line 4—4 of FIG. 3, looking in the direction of the arrows, and partially broken away to expose interior construction details.

FIG. 5 is a cross sectional view taken along Line 5—5 of FIG. 3 looking in the direction of the arrows, and partially broken away to expose details of interior construction.

FIG. 6 is a side elevational view of the device taken along Line 6—6 of FIG. 2, looking in the direction of the arrows showing the apparatus in the initial position, and partially broken away to expose interior details.

FIG. 7 is a side elevational view similar to FIG. 6, showing the arrangement of parts in the pin driving condition.

FIG. 8 is a side elevational view similar to FIG. 6 showing the position of the parts as the plunger is biased rearwardly toward its initial position.

FIG. 9 is an enlarged cross sectional view taken along Line 9—9 of FIG. 3, looking in the direction of the arrows.

DESCRIPTION OF THE PREFERRED EMBODIMENT OF THE INVENTION

Although specific terms are used in the following description for the sake of clarity, these terms are intended to refer only to the particular structure of my invention selected for illustration in the drawings and are not intended to define or limit the scope of the invention.

Referring now to FIG. 1, I show an automatic pin injector machine 10 which includes a base plate 12 upon which a forward pinning section 14 is mounted to receive a grill bar 16 therein. The pin chamber section 18 positions immediately behind the pinning section 14 and carries an inclined pin track 20 to feed pins 22 individually into the section 18 for injection into the end bores of grill bars 16. The drive section 24 aligns behind the pin chamber section 18 and includes the air cylinder 26, the trigger assembly 28 and the plunger assembly 30.

Referring now to FIGS. 3 and 4, I show the pinning section 14 provided with a horizontally aligned intake slot 32 which is shaped to snugly receive one end of a decorative grill bar 16 therein. If desired, the forward end 34 may be flared at 36 to facilitate the introduction of the grill bar 16 into the slot 32. A crank 38 pivots within the grill bar guide 40 about its pivot pin 42 from an upper position (not shown) wherein the crank 38 is urged upwardly into the intake slot 32 to a lower position wherein the crank downwardly depresses the strut 44. As illustrated in FIG. 4, when the grill bar 16 inserts into the intake slot 32, the bar contacts the crank to pivot the crank in a counterclockwise direction about the pivot pin 42. The counterclockwise movement of the crank 38 results in vertical downward movement of the strut 44 which reciprocates within an opening 46 which is provided in the base plate 12. The strut 44 in turn functions the lever 48 which has pivotal movement about its pivot pin 50. A compression spring 52 biases between the bottom of the base plate 12 and the top of the lever 48 to continuously urge the lever 48 in a counterclockwise rotation about the pivot pin 50. The

bias of the spring 52 continuously functions the lever 48 to urge the strut 44 upwardly to tend to rotate the crank 38 in a clockwise direction about the pivot pin 42 so that a portion of the crank 38 normally positions within the intake slot 32, when there is no grill bar 16 present.

As best seen in FIGS. 4 and 5, the rearward end of 54 of the lever 48 functions a vertical pin pickup 56 through a resilient connection which may be a coil 10 spring 58. As illustrated, the pin track 20 feeds pins 22 into the interior of the pin chamber section 18 at an angle of approximately 30° from the horizontal. Each pin 22 is horizontally oriented and is urged towards the vertical channel 62 within which the pin pickup 56 reciprocates. It will be noted that the pin pickup 56 is reciprocal from a lower position as illustrated in FIG. 5 to an upper position which is illustrated in dotted lines in FIG. 5. The lower position, as shown in full lines, corresponds to the position of the lever 48 when there is no grill bar 16 positioned within the intake slot 32 to thereby allow the crank 38 to clockwise rotate into the slot 32 under urging of the spring 52. When a grill bar 16 is pushed into the intake slot 32, as shown in FIG. 4, the crank 38 rotates in a counterclockwise direction 15 to downwardly push the strut 44 to pivot the lever 48 in a clockwise direction about the pivot pin 50 and against the bias of the spring 52. In this condition, the pin pickup 56 is urged to its upper position as illustrated in dotted lines in FIG. 5 to push a pin 22 upwardly to the pin driving position which aligns with the plunger pin 64 and the axial bore 66 of the grill bar 16 as hereinafter more fully set forth. It will be noted in FIG. 3 that the forward end 68 of the grill bar 16 trips the operating arm 70 of the micro switch 72 when the grill bar is fully seated within the intake slot 32 to function the air cylinder 26 in conventional manner, such as by functioning a pneumatic valve (not shown).

The air cylinder 26 is affixed to the base plate 12 and is energized by a conventional source of compressed air 40 (not shown) which is controlled by operation of the micro switch 72. The piston rod 74 is powered rearwardly by function of the cylinder 26 and is affixed to a crosshead 76 in conventional manner such as by bolting. A pair of transversely spaced draw arms 78, 80 position on either side of the piston 26 and affix to the crosshead 76 in bolted connections 82, 84. The draw arms 78, 80 forwardly connect to the sliding blocks 86, 88 which are moved relative to a base plate 12 upon function of the air cylinder 26. A trigger 90 is pivotally held between the sliding blocks 86, 88 by means of the trigger pivot pin 92. The trigger 90 terminates forwardly in a downwardly projecting hook 94 and rearwardly in an inclined surface 96 for trigger functioning purposes. The trigger 90 is normally biased in a clockwise direction about its pivot pin 92 in well-known manner such as by a spring (not shown) to continuously urge the hook 94 downwardly to engage a portion of the plunger assembly 30, as hereinafter more fully set forth.

A roller 98 is rotatively suspended upon a shaft 100 which journals within a pair of spaced, stationary blocks 102, 104 which are stationarily positioned upon the base plate 12. The roller 98 is suspended above the surface of the base plate 12 a sufficient distance to engage the trailing edge 106 of the trigger 90. Accordingly, when the cylinder 26 functions to pull the draw arms 78, 80 rearwardly, the sliding blocks 86, 88 are

also moved rearwardly to cause the inclined surface 96 to ride under the roller 98. The interaction of the inclined surface 96 and the roller 98 causes the trigger 90 to pivot in a counterclockwise direction about the trigger pivot pin 92 to thereby elevate the hook 94 for plunger release purposes.

As seen in FIGS. 1, and 2, the plunger assembly 30 is arranged for axial movement relative to the plunger block 108. The plunger assembly includes an elongate cylindrical body 110 which terminates forwardly in a cylindrical shoulder 112 and rearwardly in a trigger block 114. The plunger pin 94 axially aligns with the plunger body 110 and forwardly projects from the cylindrical shoulder 112 for pin driving purposes. The trigger block 114 includes a stop surface 116 upon which the trigger hook 94 engages in the initial position. The trigger hook 94 includes a bottom cam surface 118 and the trigger block 114 includes a cooperating upper cam surface 120. The surfaces 118, 120 slide past each other to load the plunger to its initial position following completion of a pin injection cycle. See FIG. 8.

The plunger assembly 30 includes a forward coil spring 122 and a rearward coil spring 124 for plunger operation purposes. The forward coil spring 122 biases between the forward face 126 of the plunger block 108 and the shoulder 112 and the rearward coil spring 124 biases between the rearward face 128 of the plunger block and the trigger block 114. A pair of springs 130, 132 (FIG. 1 and 2) biases between the sliding blocks 86, 88 and the fixed blocks 102, 104 to continuously urge the trigger assembly 28 to its forward position wherein the trigger hook 94 engages the trigger block 114.

In operation, a grill bar 16 is inserted into the intake slot 32 of the grill bar guide 40. As the grill bar enters the slot, it depresses the crank 38 to urge the lever 48 in a clockwise direction about its pivot pin 50 and against the bias of the spring 52. The rearward end 54 of the lever 48 pushes the pin pickup 56 upwardly within the vertical channel 60 to push a pin 22 from its lower position as illustrated in full lines in FIG. 5 to its axially aligned position wherein the pin 22 axially aligns with the plunger pin 64 and the axial bore 66 of the grill bar 16. As the grill bar is pushed further into the intake slot 32, its forward end 68 contacts the operating arm 70 which fires the micro switch 72 to thereby energize the air cylinder 26. See FIG. 3.

The energization of the air cylinder 26 pressurizes its piston (not shown) which then pushes the piston rod 74 rearwardly. The piston rod affixed crosshead 76 and the spaced draw arms 78, 80 are also pushed rearwardly by action of the air cylinder 26. The rearward movement of the draw arms 78, 80 rearwardly pulls the affixed sliding blocks 86, 88 to urge the inclined surface 96 of the trigger 90 into engagement with the underside of the roller 98 as seen in FIG. 7. The action of the roller 98 on the inclined surface 96 rotates the trigger 90 in a counterclockwise movement about the pivot pin 92 to disengage the hook portion 94 of the trigger from the trigger block 114 of the plunger assembly 30. It will be noted that as the trigger 90 is rearwardly pulled by the draw arms 78, 80, the plunger assembly 30 will also be rearwardly pulled until the hook 94 disengages from the trigger block stop surface 116. When the plunger body 110 is rearwardly pulled, the forward coil spring 122 compresses between the forward face

126 and the shoulder 112 to build up energy for pin injection purposes. When the plunger assembly fires upon lifting of the hook 94 as illustrated in FIG. 7, the build up energy of the forward coil spring 122 propels the piston body forwardly to forwardly move the plunger pin 64 within the axially aligned channels 134, 136 of the respective alignment block 138 and pin chamber block 140. The stroke of the plunger pin 64 pushes a pin 22 which has been aligned with the channel 136 by operation of the pin pickup 56 into the axial bore 66 of the grill bar 16. Preferably, the alignment block 138 is longitudinally adjustable relative to the pin chamber block 140 so that the depth of pin injection into the bore 66 can be readily controlled by means of a simple adjustment. The alignment block 138 serves as a forward stop for the plunger shoulder 112 and accordingly, this block may be used to determine the depth of pin insertion.

As may be seen in FIGS. 7 and 8, forward movement of the plunger assembly 30 compresses the rearward coil spring 124 between the plunger block 108 and the trigger block 114. Immediately following the pin insertion operation, the spring 124 acts to propel the plunger body rearwardly until the bottom cam surface 118 of the hook 94 slides upon the upper cam surface 120 of the trigger block 114. The stored energy of the coil spring 124 urges the trigger block 114 rearwardly past the hook portion 94 (FIG. 8) until the upper and lower cam surfaces 120, 118 slide clear of each other to again lock the hook 94 over the stop surface 116 of the trigger block 114 as in FIG. 6. The removal of the pin grill bar 16 and the insertion of another grill bar into the intake slot 32 acts to automatically repeat the entire cyclical operation.

Although I have described the present invention with reference to particular embodiments therein set forth, it is understood that the present disclosure has been made only by way of example and that numerous changes in the details of construction may be resorted to without departing from the spirit and scope of the invention. Thus, the scope of the invention should not be limited by the foregoing specification, but rather only by the scope of the claims appended hereto.

I claim:

1. In an automatic pin injector suitable to drive pins into the axial bore of a construction member, the combination of
  - A grill bar guide having an intake slot therein to receive one end of a construction member therein;
  - B. crank means operable within the grill bar guide from an upper position to a lower position to function a pin pickup means,
    1. a portion of said crank means extending into the intake slot when in the upper position;
    2. a pin chamber section spaced rearwardly from the grill bar guide,
      1. said pin chamber section having channel which axially aligns with the bore of the construction member,
      2. said pin chamber section including pin feed means to introduce pins interiorly,
      3. said pin chamber section including the pin pickup means to feed pins individually to the channel when the crank is moved to its said lower position;
    - D. a plunger assembly including a plunger pin which is reciprocal within the said channel for pin driving

- purposes; from a loaded position to a pin driving position;
- E. a trigger assembly operatively and releasably engaged with the plunger assembly to control the reciprocation of the plunger; and
- F. power means to move portions of the trigger assembly and the plunger assembly relative to the grill bar guide when a construction member is inserted into the said intake slot.
2. The invention of claim 1 wherein the power means include a micro switch positioned in the said pin chamber section.
3. The invention of claim 2 and a hydraulic cylinder responsive to function of the micro switch, the hydraulic cylinder acting to pull the plunger to a loaded position upon operation of the micro switch.
4. The invention of claim 3 wherein the end of the construction member functions the micro switch when the construction member fully seats within the intake slot.
5. The invention of claim 4 wherein insertion of construction member into the intake slot also operates the crank to its said lower position.
6. The invention of claim 5 wherein the trigger assembly includes a pivotal trigger, said trigger terminating forwardly in a hook and rearwardly in an inclined surface, the said hook releasably engaging the said plunger assembly.
7. The invention of claim 6 and a roller positioned rearwardly of the trigger, the said inclined surface interacting with the roller to pivot the trigger when the

- power means pull the trigger rearwardly to thereby release the hook from the plunger assembly.
8. The invention of claim 7 wherein the plunger assembly includes a stationary plunger block and a plunger body which is reciprocal with respect to the plunger block, said plunger body terminating forwardly in a shoulder and rearwardly in a trigger block, the said plunger pin projecting forwardly from the shoulder.
9. The invention of claim 8 wherein a first spring biases between the plunger block and the shoulder, said first spring building up energy when the trigger assembly is pulled rearwardly, said energy propelling the plunger forwardly for pin driving purposes when the hook is released from the plunger assembly.
10. The invention of claim 9 and a second spring which biases between the plunger block and the trigger block, said second spring building up energy when the plunger is propelled forwardly, said energy serving to urge the plunger rearwardly following completion of the pin driving until the hook reengages the plunger assembly.
11. The invention of claim 10 wherein the said hook releasably engages the trigger block.
12. The invention of claim 11 wherein the hook is provided with a bottom cam surface and the trigger block is provided with an upper cam surface, the said upper and lower cam surfaces sliding relative to each other as the plunger is propelled rearwardly, said cam surfaces interacting to pivot the trigger to allow the hook to engage the trigger block.
